(57) **CLAIM**

The ornamental design for a wheel for automobile, as shown and described.

DESCRIPTION

FIG. 1 is a front perspective view of a wheel for automobile; and,

FIG. 2 is a front elevation view thereof.

The ghosted showing of the barrel, lug holes and valve stem hole illustrate portions of the wheel for automobile that form no part of the claimed design.

1 Claim, 2 Drawing Sheets

FIG. 1

FIG. 2
